UNITED STATES PATENT OFFICE.

SWAN O. THORELL, OF DENVER, COLORADO.

FOLDABLE SQUARE.

1,340,125.

Specification of Letters Patent.

Patented May 11, 1920.

Application filed April 4, 1918. Serial No. 226,686.

To all whom it may concern:

Be it known that I, SWAN O. THORELL, a citizen of the United States, residing at Denver, in the county of Denver and State 5 of Colorado, have invented certain new and useful Improvements in Foldable Squares; and I do hereby declare the following to be a full, clear, and exact description of the invention, such as will enable others skilled 10 in the art to which it appertains to make and use the same.

This invention relates to instruments of precision and more particularly to a foldable square. It has been proposed to fold, 15 or relatively collapse, the angularly disposed blades or legs of squares but because of this foldable construction the parts are likely to have a slight play, especially when in the angularly set position, and thus this 20 destroys the absolute accuracy of the square.

It is one of the objects of the present invention to provide for the accuracy of the instrument when it is adjusted as a square and it is a further object of the invention to 25 provide for the ready locking of the foldable parts of the square in either set or collapsed position. It is a further object of the invention to provide a device of this type which will not only be as substantially accurate as a rigid square but which will be 30 easily adjustable, readily locked in either of its positions and which shall be simple, practicable, inexpensive and durable.

With these and other objects in view, as 35 will be readily understood by those versed in the art, the invention consists of a square having relatively foldable parts and in means for locking the parts and in details and arrangements as described hereinafter 40 with relation to a form of the invention illustrated in the accompanying drawing, in which—

Figure 1 is a plan view of the jointed ends of a fragment of the square,

Fig. 2 is a similar view taken from the opposite side of the square,

Fig. 3 is a transverse section on line 3—3 of Fig. 1,

Fig. 4 is a section on line 4—4 of Fig. 2,

Fig. 5 is a section on line 5—5 of Fig. 2;

Fig. 6 is a plan view of the unfolded or set members looking toward the same side as in Fig. 1,

Fig. 7 is a sectional view on line 7—7 of Fig. 6,

Fig. 8 is a fragmentary view showing the

spring detent as sprung upwardly to release the members,

Fig. 9 is a bottom plan view of Fig. 6, and Fig. 10 is a section on line 10—10 of Fig. 9.

In its illustrated embodiment, the invention comprises what may be termed an elbow arm, A, and a straight blade, B. The short arm of the elbow member, A, extends 65 at right angles from the main body and is shown as of about one-half the thickness of main member, A, so that it will overlap the complementary recessed portion of the adjacent end of the blade, B, and so that the 70 top and bottom surfaces of these members A and B are respectively flush. The elbow arm and the recessed end of the member, B, are pivotally connected together by means of a suitable device in the form of a screw, 75 2, having a large flat end, 3, overlapping a seat countersunk in the short arm of the arm, A, the threads of the screw engaging in the adjacent end of the blade, B. For the purpose of securing accuracy of adjustment 80 of the parts and to eliminate unnecessary play, the elbow arm, A, is provided at the end of its elbow with an arcuate edge, 4, having a lip, 5, adapted to enter an undercut arcuate seat or groove, 6, concentric to the 85 center of the screw, 2, and formed in the adjacent edge of the blade, B. To limit the outward swinging movement of the blades about the pivot screw, 2, the arcuate edge intersects a straight transverse shoulder, 7, 90 of the elbow arm and this is adapted to be abutted by a similar straight shoulder, 8, at the complementary portion of the blade, B. Coöperative with the interengaged lip, 5, and groove, 6, to guide the folding movement, the end of the blade, B, which is diametrically opposite to the groove, 6, is provided as shown in Fig. 7 with a lip, 10, running in a groove, 11, curved concentrically with the axis of the screw, 2, so that when 100 the members A—B are set at right angles to each other, the parts are held against relative play.

One of the important features of the present invention resides in means for readily locking the arm, A, and the blade, B, either in the set right angular position, Figs. 6 and 9, or in the folded position, Figs. 1 and 2. To effectually, easily, and inexpensively, secure the locking of these members, there is clearly 110 shown in Figs. 7 and 8 a device comprising a flat spring finger or detent, 15, which is

riveted or otherwise secured at one end at, 16, to the body of the blade, B, while its opposite and yielding end is adapted to be pressed upwardly from the chamber 17, in 5 which it may lie flush with the top plane of the blade, B, by the application of pressure, as, for instance, from one of the fingers or thumb against a button, 19, secured to the lower face of the finger, 15, and playing in an aperture, 20, provided therefor in the underlying portion of the blade, B.

The end of the finger, 15, may be, and in the present case is, shown as being beveled downwardly and rearwardly, as clearly appears at Fig. 8. When the square is folded, as in Fig. 1, the end of the finger, 15, will rest against the adjacent edge of the arm of the elbow member, A, and will thus prevent movement of that arm and thereby 20 will act as a lock, locking this square in folded position. When the end of the finger, 15, is beveled as here shown, it is found preferable to provide an indentation, or recess, 21, in the said edge of the arm of the 25 elbow, in which recess the extreme end of the finger 15 will rest when the square is in folded position. For locking the square in open position a notch, 22, is provided in the said short arm of the elbow member, A, said 30 notch being constructed to exactly accommodate the end of the finger, 15, when the arms are in right angle position, as shown in Figs. 6 and 9.

It will be evident that when the square is 35 in folded position the spring finger, 15, will automatically spring into engagement with the edge of the short arm and lock the same as hereinabove described and, likewise, when the arms are in right angle position this 40 finger will automatically engage the notch 22 and lock the square in open position, as above described.

To change the square from one position to the other it is only necessary to raise the 45 end of the spring finger, 15, by pressure on the button, 19, as indicated at Fig. 8. The spring, 15, in order that it may, when in normal position, be flush with the surface of the blades, is preferably mounted in a 50 groove or depression, 15^a, in the blade, B, and, in order that the locking of the arms in right angle position may be more secure and exact, this groove is so constructed that when the blades are in right angle position 55 the notch, 22, and the groove, 15^a, will be in exact alinement so that the spring, 15, will fit snugly in both continuously.

What is claimed is—

1. A square having a pair of flat pivoted 60 members to open or close, one of the members having a short elbow arm, the transverse edge of said short arm and the adjacent part of the other member being provided with interlocking, undercut and overlying guide means concentric with the axis 65

of the pivot, the elbow having an inside edge perpendicular to its blade, and a detent relatively engageable with the inside and transverse edges.

2. A square having a pair of flat pivoted 70 members to open or close, one of the members having a short elbow arm having an arcuate transverse edge deeply notched, said short arm and the adjacent end of the other member being provided with interlocking, undercut and overlying guide means concentric with the axis of pivot, and a resilient finger attached to the pivoted end of one member for interlocking with deep notch of the short arm and engaging a 80 notch in a side of the elbow when the arms are in the opened or closed positions.

3. A square having blade members, one of 85 said members having an elbow with a notch in one edge thereof, and the other member having a countersunk detent adapted to engage said notch when the blades are in right angle position, said detent being likewise adapted to engage said elbow member when the square is in folded position, the detent 90 being operable by pressure applied thereto from the opposite face of the member on which it is mounted, the member carrying the detent having a finger hold provided for access to the detent. 95

4. A square having blade members mutually recessed and overlapping jointed ends whereby the blades may be adjusted in parallel or right angular relation, one of said members having an elbow with an edge 100 thereof notched and the other member having a detent to engage said notch to lock the members in right angular relation, said detent being countersunk and having a part exposed at its opposite base of its carrying 105 member to be lifted from its seat by pressure against said part.

5. A square having a pair of flat pivoted 110 members adapted to be disposed either parallel or perpendicular to each other, each of said members being provided with a straight edge, one of the members having an elbow with one edge perpendicular to said straight edge and an arcuate edge around its end and opposite to the straight edge, a stop 115 shoulder at one side of the arcuate edge, the other member having a stop shoulder engageable with the aforesaid stop shoulder, said short arm and the adjacent end of the other arm provided with interlocking, undercutting and underlying, guide means at the arcuate edge and concentric with the axis of the pivot, and a resilient finger attached to the pivot end of one member for interlocking 120 with the arcuate edge of the short elbow and also with the straight edge. 125

In testimony whereof he affixes his signature.

SWAN O. THORELL.
